UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

CONSTRUCTION FOR BEAMS.

1,335,407.

Specification of Letters Patent. Patented Mar. 30, 1920.

Application filed March 5, 1918. Serial No. 220,485.

To all whom it may concern:

Be it known that I, WALTER I. TUTTLE, a citizen of the United States, and a resident of Providence, in the county of Providence and State of Rhode Island, have invented an Improvement in Construction for Beams, of which the following is a specification.

This invention relates to the construction of warp beams and the like. One of the objects of this invention is to provide a simple and practical beam construction of great durability. Another object is to provide an improved construction of the above type in which the working and other stresses are so distributed as to insure a high degree of rigidity and strength without impairment of efficient action. Other objects will be in part obvious and in part pointed out herein-after.

20 The invention accordingly consists in the features of construction, combinations of elements and arrangement of parts which will be exemplified in the structure hereinafter described and the scope of the application 25 of which will be indicated in the appended claims.

In the accompanying drawing, in which is shown one of various possible embodiments of this invention.

30 Figure 1 is an end view;

Fig. 2 is a sectional view taken along the line 2—2 of Fig. 1 and Fig. 3, and,

Fig. 3 is a section taken along the line 3—3 of Fig. 2.

35 Similar reference characters refer to similar parts throughout the several views of the drawing.

Referring to Fig. 2 of the drawing there is shown a cylinder 10 of the warp beam 40 preferably of a built-up construction and composed of the longitudinally extending wooden members 11 suitably secured circumferentially about a heavy wooden cylinder or abutment 12. The elements 11 of the cylinder 10 are secured to the abutment 12 preferably by means of spikes or screws. Passing co-axially through the cylinder 10 and through the abutment 12 is a shaft 13, and while only a section of one end of the warp beam is shown in Fig. 2, it is to be understood that the end and head construction of this warp beam is identical at both ends. The shaft 13 passes through an abutment 45 similar to the abutment 12 at the opposite end of the cylinder 10. It may be noted

here that the term "cylinder" is used throughout broadly to denote any equivalent part in warp beam construction, the cylinder 10 herein described being the preferred embodiment of this invention.

60 Recessed in the outer surface at the end of the cylinder is a stress distributing member 14 composed preferably of a heavy sheet metal of like cylindrical form and having its ends joined preferably by means of a riveted butt-joint 15. The member 14 is recessed in the cylinder 10 to such an extent that its outer surface will substantially coincide with the surface of the cylinder 10 so that the latter will be substantially uninterrupted 65 and is secured thereto by means of screws 16 which are counter-sunk within the member 14 so as to leave the outer surface of the latter smooth and unbroken. The screws 16, by which the member 14 is secured to the 70 cylinder 10, are uniformly distributed both circumferentially and in an axial direction for a purpose to be hereinafter described in detail. The end surface of the member 14 is 75 substantially flush and coincident with the end surface of the cylinder 10 itself, to form an end bearing surface 17.

80 Mounted upon the shaft 13 is a cast abutment 18 bearing against the central wooden abutment 12 and held against rotation with 85 respect to the latter by means of the spurs 19. The cast abutment 18 provides an outer bearing surface 20, which is preferably in the plane of the bearing surface 17 at the end of the cylinder. Bearing against the 90 surface 20 of the cast abutment 18 is a cast hub member 21 mounted upon the shaft 13 and adjustably held in position with respect to the bearing surface 20 by means of the locknuts 22 on the shaft 13.

95 Extending outwardly from the cast hub 21 and integral therewith is a flange 23 to which is secured a sheet metal head member 24 as by rivets 25. The head member 24 is substantially annular in form and has extending through its central opening that portion of the hub 21 which engages with the bearing surface 20 on the cast abutment 18. The head member 24 has its entire central portion stamped outwardly to form an 100 annular depression which rests evenly against the flange 23 and in which annular depression are applied the rivets 25. Extending in a radial direction and from the annular depression is a series of radial ribs 105 110

26, which are stamped outwardly into the plane of the annular depression, hereinbefore described.

The head member 24 bears evenly against 5 the composite end surface 17 of the cylinder, and the flange 23 extends outwardly to a sufficient extent so that it securely grips and holds the head member 24 in bearing position against the surface 17. The flange 10 23 engages the radial ribs 26 at their outer surface and transmits both directly and through them any desired degree of gripping or supporting pressure with which the sheet metal head member is held in frictional 15 contact with the end surface 17. Any desired degree of gripping pressure may be exerted by means of the adjustable lock nuts 22, whereby the frictional contact between the head member 24 and the cylinder end 20 surface may be varied at will.

A belt race 27 may be formed in the outer edge portion of the head member 24 extending beyond the cylinder 10.

In order that the action of the construction above described may be better understood, it is pointed out that a wooden barrel or cylinder possesses many advantages in beam construction but is susceptible to injury which renders it substantially useless. Obviously the end of the cylinder must fit snugly against the adjacent head, or threads of the warp at the end will enter the crevice and become entangled therein. Also the projecting portions of the cylinder beyond abutment 12 must be able to stand considerable stresses while subjected to various incidents in their use not only when filled but when, as is often the case, piled one upon the other with the heads overlapping and thus subjected to an inward crushing stress. By a device such as that herein described, the pressure of the head even though unevenly applied is uniformly distributed throughout the end of the cylinder. Also, the outer surface of the cylinder at its ends being provided with the member 14 which may act as a tension member, prevents an inward crushing of the parts with a tendency to open a crevice between the cylinder and the adjacent head.

It will thus be seen that by the use of this device which may be of any suitable material and which may be considerably modified in form, the beam is rendered well adapted 55 to stand up under hard conditions of use and maintain a smooth even surface snugly fitting against the adjacent head.

As various possible embodiments might be made of the above construction and as various changes might be made in the embodiment above set forth, it is to be understood that all matter herein set forth or shown in the accompanying drawings is to be interpreted as illustrative and not in a limiting sense. 60

What I claim is:

1. In a construction of the class described, in combination, a hollow wooden cylinder member built up of a plurality of longitudinal sections, a supporting abutment 70 fitted within said cylinder and spaced from the end thereof, a head member secured against the end of said cylinder, and a flat annular member fitted about said cylinder sections and extending from over said abutment to the inner surface of said head, said annular member being of relatively high tensile strength, whereby the projecting ends of said cylinder members are tied together and shielded against external shock. 80

2. In a construction of the class described, in combination, a cylinder comprising a hollow wooden shell, a central cast abutment mounted within said shell, an annular sheet metal head member resting in engagement 85 with the end surface of said wooden shell, a shaft passing centrally through said shell, a head casting on said shaft resting against said abutment and extending outwardly to support the outer surface of said sheet metal 90 head member opposite its engagement with the end surface of said shell, means on said shaft for forcing said head casting against said abutment and grip said head member between itself and said cylinder, and means 95 mounted on said shell for receiving and distributing stresses transmitted from said head member.

3. In a construction of the class described, in combination, a hollow wooden cylinder 100 and a head member and a supporting member within said cylinder and spaced from said head member whereby the end of said cylinder projects beyond the said supporting member, means adapted to hold said 105 head member against the end of said cylinder, and a sheet metal cylinder device set into the outer surface of said cylinder over said supporting member and extending to said head member. 110

In testimony whereof I have signed my name to this specification this 25th day of February, 1918.

WALTER I. TUTTLE.
